DESIGN FOR A SWING JOINT

Dwight M. Phillips, Fullerton, Calif., assignor to
Chiksan Tool Company, Brea, Calif., a corpora-
tion of California

Application April 27, 1943, Serial No. 110,061

Term of patent 14 years

To all whom it may concern:

Be it known that I, Dwight M. Phillips, a citizen of the United States, residing in the city of Fullerton, county of Orange, and State of California, have invented a new, original, and ornamental Design for a Swing Joint, of which the following is a specification, reference being had to the accompanying drawing, forming a part thereof.

Fig. 1 is an end view of a swing joint showing my new design; Fig. 2 is a side elevation of the swing joint; and Fig. 3 is a transverse sectional view of the upper pipe portion in Fig. 2 taken as indicated by the lines 3—3 on Fig. 2.

I claim:

The ornamental design for a swing joint, as shown.

DWIGHT M. PHILLIPS.
